US00D843324S

(12) **United States Design Patent** (10) **Patent No.:** **US D843,324 S**
Read et al. (45) **Date of Patent:** **** Mar. 19, 2019**

(54) **WALL MOUNTABLE CONNECTOR WITH TERMINAL LABELS**

(71) Applicant: **Ademco Inc.**, Golden Valley, MN (US)

(72) Inventors: **Travis Read**, Little Canada, MN (US); **David J. Emmons**, Plymouth, MN (US); **Jonathan Erbacher**, Minneapolis, MN (US); **Rajat Shail**, Stevensville, MI (US)

(73) Assignee: **Ademco Inc.**, Golden Valley, MN (US)

(**) Term: **15 Years**

(21) Appl. No.: **29/581,833**

(22) Filed: **Oct. 21, 2016**

Related U.S. Application Data

(63) Continuation-in-part of application No. 15/042,397, filed on Feb. 12, 2016, now Pat. No. 9,735,518.

(57) **CLAIM**

The ornamental design for a wall mountable connector with terminal labels, as shown and described.

DESCRIPTION

FIG. 1 is a front elevation view of a wall mountable connector with terminal labels showing our new design; FIG. 2 is a perspective view of the wall mountable connector of FIG. 1 taken from a leftward vantage point; and, FIG. 3 is a perspective view of the wall mountable connector of FIG. 1 taken from a rightward vantage point.

The broken line represents unclaimed environment structure only and forms no part of the claimed design.

1 Claim, 3 Drawing Sheets
